UNITED STATES PATENT OFFICE.

MILTON HARTMAN, OF DETROIT, MICHIGAN.

COMBINED ADDRESSING AND LISTING DEVICE.

1,425,768.

Specification of Letters Patent. Patented Aug. 15, 1922.

Application filed November 6, 1920. Serial No. 422,354.

To all whom it may concern:

Be it known that I, MILTON HARTMAN, a citizen of the United States of America, residing at Detroit, in the county of Wayne 5 and State of Michigan, have invented certain new and useful Improvements in Combined Addressing and Listing Devices, of which the following is a specification, reference being had therein to the accompanying 10 drawings.

This invention relates to a combined addressing and listing device and refers more particularly to a combined addressing and listing system wherein there is a new and 15 improved arrangement of charts of analysis sheets in which the listing is made in such a manner as to be available without recopying for use both as a reference record and as a direct mailing list; that is, one from which 20 the individual names and addresses can be severed and directly applied to the advertising matter or other matter to be mailed.

The invention also resides in the novel arrangement whereby after the data is once 25 compiled it can be used without rewriting for the purpose of either a permanent record from which certain selective data is available or as a direct mailing or addressing list. The invention also resides in the 30 novel arrangement for eliminating the inaccuracies due to numerous rewritings of a list; in the arrangement for simplifying the finding of certain selective data; and in the avoidance of the expensive, wasteful and 35 slow systems and devices previously used.

Other features of the invention reside in the novel arrangement for listing the data of the various towns, etc. in overlapping relation so as to make more readily available 40 the finding of the data required and in so arranging the various town cards or the like that numerous additions can be made within the limits of the device, and in such other features of construction and arrangement 45 and method as will more fully hereinafter appear.

In the drawings:

Figure 1 is a plan view of one of the master record charts;

50 Figure 2 is a plan view of one of the master town record charts;

Figure 3 is an assembly of the charts shown in Figure 2;

55 Figure 4 is a cross-section on the line 4-4 of Figure 3;

Figure 5 is a plan view of one of the completed addressing and listing devices;

Figure 6 is a plan view demonstrating one form of data or original list from which the combined addressing and listing chart 60 is obtained.

While my invention in its broader aspects is not limited to the particular use described, I will for the better understanding of the invention describe the combined addressing 65 and listing device in connection with data relating to automobiles.

In order to better appreciate the advantages of such a combined addressing and listing device attention is called to the fact 70 that there are three principal uses for a list of automobile owners; first, statistical; second, sales promotion; third, advertising administration. Under the statistical heading there is a large use on the part of automobile tire, accessory manufacturers, etc., and many other members of the automotive industry require basic figures upon which to establish their quotas of sales expectancies to gauge their protection to diffuse distribution, to locate sales resistance and to 75 make comparative statements. For this purpose, however, the information is required to be arranged by towns showing how many car owners there are in each town, and 80 further assembled according to county or similar units. It is also necessary for this statistical list to show how many of each 85 make of car there are in the principal cities.

Under the second heading of sales promotion it is to be noted that there is a constantly increasing use for a list of automobile owners to be acquainted with the merits of the various automotive accessory and services in sales promotion activity. 90

Under the third heading of advertising administration it is possible with such a list to predetermine editions of printed matter so as to properly estimate the amount required to cover the car owners in any town 100 or numbers of towns, or size of towns or the car owners of certain makes of car in any community or in any number of communities. Moreover as the automobile owner is a representative citizen, such a list 105 in addition to being available for purely automobile purposes is also capable of use in the advertising and sales of other articles, thus making a listing of car owners an ideal list for direct advertising pur- 110

poses. Such a list must be arranged by towns and counties, not alone for convenience in entering the mailing matter in the postoffice, but to make possible the association of the names and dealers in the locality of the car owner where the product advertised is on sale. This arrangement of a combined addressing and listing device whereby all the matter can be mailed 10 by towns to the persons properly selected as interested within such towns or postoffice areas is also an important feature of the invention. As is well known, it is customary for each of the States to maintain a book or 15 other list in which there is data pertaining to automobile registrations showing the serial number of the car, the make and year of the car and on the same line the name, street number and town of the owner of the 20 car. There is, however, no uniformity among the various States as to the manner of keeping this data but it is generally kept available by consecutive license numbers for the State, as illustrated in Figure 6.

25 In the advertising of various automobile parts or accessories such as tires, carburetors, lubricants, etc, it often happens that the product advertised is applicable only to a single make of car or a single class of cars. 30 In other words, certain carburetors may be applicable only to cars having a particular form of manifold or again other accessories, lubricants or other material may be applicable only to cars put out to the trade 35 at an initial selling price above a given figure. It is therefore obvious that in advertising these particular lines, to mail a copy of the advertising matter to every car owner in a given county or locality would 40 be extremely wasteful, and various attempts have been made to compile lists showing this selective data. Such previous attempts have required rewriting the entire list and then putting it on card systems or other arrangements 45 from which the user rewrites the list each time the addressing or mailing list is made up. Such arrangements are not only slow but greatly increase the chances for inaccuracy and it is one of the 50 objects of the present invention to provide a system having a combined addressing and listing device in which a single writing at the time of compiling the original data is all that is required.

55 Taking up now in detail the various individual operations, it will be noticed in Figure 6 that the original data is arranged in serial number but without reference to either the make of the car or the locality 60 in which the owner resides. This data is first copied on a master record chart shown in Figure 1, this chart A being as illustrated of a size approximately 34 inches long by 22 inches wide and arranged to cut into 65 six strips each strip B being 34 inches long

by 3.7 inches wide, these figures being for the purpose of illustrating the relative proportion of the parts for the purpose herein-after brought out in detail. Each of the strips B is designed so that it contains two columns preferably arranged on opposite sides of a separable line C, the right hand column being 2.3 inches wide and the left hand column being 1.4 inches wide and having at the extreme left a marginal portion 70 three-tenths of an inch wide, the purpose of this marginal portion being to aid in affixing the strip when mounting the same on the town card. From top to bottom this strip B contains 51 spaces, each space being 75 two-thirds inch high. The purpose in designing the sheet in blocks two-thirds inch high being to permit of four typewriter spaces, the maximum of three typewriter 80 spaces being required for a three line name, street address and town, the fourth space 85 permitting of the separation on the line D between the blocks. Preferably in writing up the State car registration on sheets, such as the sheet A, hectograph typewriter ribbons are used which makes possible the 90 producing of many copies from the original writing.

In compiling the list it is done in such a manner that for each car owner item the 95 license number and the make of the car appear in the left hand block, and the name, street address, town and State appear on that portion of the chart at the right of the separable line portion showing in the particular construction as a perforated line C. Where multiple ownership appears in consecutive license order ditto marks only will appear in the right hand column as indicated by G, but the license number and 100 make of the car will duly appear in the column E. One of the purposes of this arrangement is to provide a check in addressing, so as to avoid waste in sending more 105 than one copy of the advertisement to any 110 particular addressee. It, however, still permits of selection by make of car and does not interfere with the compilation of the total number of cars in a town regardless of the net ownership. For instance, if a creamery company owned four trucks and two pleasure cars over \$3000.00 value and six cars under \$3000.00 value and if it is desired 115 to mail to this company advertising matter pertaining only to pleasure cars of \$3000.00 value or to trucks it would still be possible to make the selection by car from the left hand column E, but in mailing the advertisement relating to trucks to such company only one piece of advertising would be 120 mailed as the addressing list would show by the ditto mark that he owned a plurality of trucks and therefore in applying the addressing labels those bearing only the ditto 125 marks would be omitted.

After the master record charts A are compiled the sheets are separated into the master record chart strips B and these are again separated on the lines D and then subsequently arranged according to towns. These resultant blocks are then sorted according to town or postoffice and secured in corresponding spaces on the master town record chart N shown in Figure 2.

It will be noticed that this master town record chart, which is preferably made on tough manila stock is 18 inches long by five and one half inches wide and it is designed to correspond with the ruling of the master record chart shown in Figure 1, the spaces being $\frac{3}{8}$ inch high, the right hand column 2.3 inches wide and the left hand column 1 inch wide and the margin four-tenths inch wide, there being preferably 27 of such spaces or blocks. In the top space the town, county, State and code number appear preferably in a different color from that in which the body of the data is written and this town card has an adhesive surface in the four-tenths inch wide column and a one and one-sixteenth inch wide adhesive surface at the extreme right hand column. After the originally written master record charts are separated, the individual blocks J are mounted on the master town record chart by moistening the adhesive portions H and H' and affixing the blocks J to such adhesive portions. The numbering of the master town record charts sequentially as indicated at I makes possible a visible count as the numbers I are obscured by mounting additional strips so that the number appearing immediately below the last mounting strip is a total for that particular town card. At the left of the adhesive portion H' there is a marginal column L on which appears a panel of summarization of a large number of the principal makes of automobiles with a space M permitting the recording of a figure showing how many cars of that make there are in that particular town, the name of which town appears at the top of this particular master town record chart N. Beneath the summary space there is provided a suitable place for recording additional data such as the date when the record was made, the name or number of the operator, date of filing, etc.

These built-up town cards are then assembled by counties according to code number so as to materially reduce the bulk to be handled when looking for data as to a particular locality.

Moreover each group of town cards is assembled in a county unit so as to be arranged in a visible manner. Near the left hand portion of each town card there are a series of equally distant spaced perforations O' and on the left hand marginal portion of the back O there are similarly spaced per-

forations, this back O being of a greater length than the individual master town card chart N so that the plurality of the charts N can be arranged in a single back as shown in Fig. 4 by affixing one or more rings Q through the perforations O' and the corresponding perforations R in the back O. These completed master town record charts N with the names mounted thereon can be filled in at any arbitrary time but reproduced in blocks of 10 or more by one of the standard commercial gelatin surface transfer machines to sheets which are then cut into strips S which are a reproduction of the master town record chart N and as the strips S have an extra block T at the bottom it is possible to attach a large number of these strips together in a roll which can be used in the ordinary mailing machines for concerns which have large mailing requirements.

The purpose of making the right hand column G a width of two and one-half inches is for the purpose of allowing this strip when separated as on the line corresponding to the line C to be run through an ordinary commercial mailing device which as illustrated handles a sheet of this width. These strips are merely pasted end to end, rolled up and automatically affixed to advertising matter by means of the automatic mailing device or they may be separated by hand and directly affixed by hand to the matter to be mailed. The colored town heading U can be used as a signal when running through the lists to flag or otherwise note the change in town and also it can be affixed to the package containing all the advertisements for any given town, which both separates the mailing material and facilitates the handling of the advertising matter through the mails.

It will be noticed that in my combined addressing and listing device the complete data for both the selective purposes and as a mailing list is obtained by a single writing and that the one and same chart is available for statistical purposes or can be separated and as on the perforated line V and used as direct labels ready to be affixed to advertising matter without rewriting.

What I claim as my invention is:

1. In a combined listing and addressing device, a chart having a longitudinally extending separable line portion, selective data located on one side of said separable line portion and the mailing address of the party to whom the selective data applies located on the opposite side of said separable line portion, and in operative relation to the corresponding selective data, said addresses being arranged in blocks suitable for individual mailing purposes when separated from the adjacent address blocks.

2. In a combined listing and addressing

device, a chart having a longitudinally extending separable line portion, selective data located on one side of said separable line portion and the mailing address of the party to whom the selective data applies located on the opposite side of said separable line portion, and in operative relation to the corresponding selective data, said addresses being arranged in blocks suitable for individual mailing purposes when separated from the adjacent address blocks, said separable line portion constituting a series of perforations.

3. In a combined listing and addressing device, a chart having a longitudinally extending separable line portion, selective data located on one side of said separable line portion and the mailing address of the party to whom the selective data applies located on the opposite side of said separable line portion, and in operative relation to the corresponding selective data, said addresses being arranged in blocks suitable for individual mailing purposes when separated from the adjacent address blocks, the mail-

ing address of the party comprising the name and address arranged on lines one above another whereby the block bearing the address when separated from the adjacent blocks is in suitable form to be directly affixed to an article to be mailed as the mailing address.

4. In a combined listing and addressing device, a chart having selective data, and the mailing address of the party to whom the selective data applies arranged in operative relation to the corresponding selective data, said addresses being arranged in blocks suitable for individual mailing purposes when separated from the adjacent address blocks, the mailing address of the party comprising the name and address arranged on lines one above the other whereby the block bearing the address, when separated from the adjacent blocks is in suitable form to be directly affixed to an article to be mailed as the mailing address.

In testimony whereof I affix my signature,
MILTON HARTMAN.
